UNITED STATES PATENT OFFICE.

JAMES D. ERSKINE, OF CHICAGO, ILLINOIS.

HEATER.

No. 818,085.

Specification of Letters Patent.

Patented April 17, 1906.

Application filed February 18, 1905. Serial No. 246,331.

To all whom it may concern:

Be it known that I, JAMES D. ERSKINE, a citizen of the United States, residing at Chicago, in the county of Cook and State of Illinois, have invented certain new and useful Improvements in Heaters, of which the following is a specification, reference being had therein to the accompanying drawings.

- The invention relates particularly to a heating mechanism designed for increasing the humidity in a room, utilizing not only the heat from a radiator for this purpose, but also the air-currents caused by the same; and it consists of a heater of any preferred type and a receptacle containing water, associated with means for compelling the passage of the hot air across the receptacle, whereby a maximum amount of moisture is carried away into the room for the purpose set forth.
- The invention further consists in the peculiar arrangement and combination of the various parts of the mechanism and the various details of construction, as hereinafter described.
- In the drawings illustrating my invention, Figure 1 is an end elevation of a preferred form of the heating mechanism. Fig. 2 is a front view thereof; and Fig. 3 is a fragmentary perspective view of the receptacle, showing one of the preferred means of support.

The reference-letter A represents a heater, which may be of any desired construction, in this instance a radiator of usual form.

B represents a shield for the radiator, of any ordinary type, having the usual section B', overhanging the radiator-top, as indicated in Fig. 1, and C represents a water-receptacle arranged in this case intermediate the top of the radiator and the overhanging portion of the shield and mounted in bearings, as hereinafter more fully described, for lateral or other movement, whereby it may be moved outwardly from beneath the shield to permit of its being cleansed and filled.

Preferably the pan is supported from the 45 overhanging section B', brackets *a* being secured to the under face of the shield at the end portions thereof, so that the pan is substantially the length of the radiator, and links *b*, connecting the pan ends with the 50 brackets, as plainly illustrated in Fig. 3. The pan is thus mounted in rocking bearings, permitting the lateral movement desired, and at the same time is spaced from the shield and radiator-top, so as to permit the 55 air-currents to pass over and beneath the pan. This is the desirable location for the pan, as it permits the heat rising from the radiator to strike directly against the pan, thereby heating its contents and the air-currents to pass over the water in the pan, and thus become moistened, a maximum amount of moisture being carried away into the 60 room as fast as the water is evaporated.

It will be obvious from the construction as 65 described that while the best results are obtained by arranging the pan in the manner set forth it may be associated with the shield and heater in various other ways without in any manner departing from my invention. 70 It is also to be noticed that while the usual shield is shown as a guide for the air-currents any form of guide that will compel the heated air to pass over the open top of the receptacle will serve the purpose. 75

What I claim as my invention is—

In a heater, the combination, with a radiator, of an overhanging shield therefor, and a laterally-movable water-pan supported in movable bearings depending from the overhanging portion of the shield. 80

In testimony whereof I affix my signature in presence of two witnesses.

JAMES D. ERSKINE.
